Patented Jan. 22, 1974

230,090

POWER OPERATED HORN

Michael Pappas, Irvington, N.J., assignor to Falcon
Safety Products, Inc., Mountainside, N.J.

Filed Aug. 16, 1971, Ser. No. 172,357

Term of patent 14 years

Int. Cl. D29—99

U.S. Cl. D72—1 C

FIG. 2

FIG. 1

FIG.3

FIG.4

FIG.5

FIG. 1 is a front view of a power operated horn showing my new design;

FIG. 2 is a rear view thereof;

FIG. 3 is a top plan view thereof;

FIG. 4 is a side view thereof, both sides being identical;

FIG. 5 is a bottom view thereof.

The cylinder is shown in broken lines for illustrative purposes only.

I claim:

The ornamental design for a power operated horn, substantially as shown and described.
